Primary Examiner — Ricky Pham*(74) Attorney, Agent, or Firm* — Dunlap Bennett & Ludwig PLLC(57) **CLAIM**

The ornamental design for a skewer stand, as shown and described.

DESCRIPTION

FIG. 1 is a top perspective view of a skewer stand; FIG. 2 is a right side elevation view thereof, the left side elevation view being a mirror image thereof;

FIG. 3 is a front elevation view thereof, the rear elevation view being a mirror image thereof;

FIG. 4 is a top elevation view thereof; and,

FIG. 5 is a bottom elevation view thereof.

The broken lines shown in the drawings depict portions of skewer holders that form no part of the claimed invention.
